Primary Examiner — Richard Edgar*Assistant Examiner* — Jessica Ruth Grable(74) *Attorney, Agent, or Firm* — Kevin Paganini, Esq.(57) **CLAIM**

The ornamental design for a furniture panel set as shown and described.

DESCRIPTION

FIG. 1 is a front perspective view of the furniture panel set; FIG. 2 is a bottom perspective view thereof;

FIG. 3 is a rear perspective view thereof;

FIG. 4 is a front view thereof;

FIG. 5 is a top view thereof;

FIG. 6 is a bottom view thereof;

FIG. 7 is a rear view thereof;

FIG. 8 is a side view thereof; and,

FIG. 9 is an opposite side view thereof.

The broken lines shown in the drawings illustrate portions of the furniture panel set that form no part of the claimed design.

1 Claim, 7 Drawing Sheets(56)
